(57) **CLAIM**

The ornamental design for a nasal spray device, as shown and described.

DESCRIPTION

FIG. 1 is a perspective view of the nasal spray device.

FIG. 2 is another perspective view of the nasal spray device.

FIG. 3 is a side view of the nasal spray device.

FIG. 4 is a back view of the nasal spray device; and,

FIG. 5 is another side perspective view of the nasal spray device with the cap removed and a compartment open.

The broken lines in the drawings illustrate portions of the nasal spray device that form no part of the claimed design.
